UNITED STATES PATENT OFFICE.

HARRY O. DAVIDSON, OF CLEVELAND, OHIO, ASSIGNOR TO THE HYDRAULIC PRESSED STEEL COMPANY, OF CLEVELAND, OHIO, A CORPORATION OF OHIO.

CONCRETE FORM.

1,349,819.

Specification of Letters Patent. Patented Aug. 17, 1920.

Application filed November 13, 1916. Serial No. 130,945.

To all whom it may concern:

Be it known that I, HARRY O. DAVIDSON, a citizen of the United States, residing at Cleveland, in the county of Cuyahoga and State of Ohio, have invented a certain new and useful Improvement in Concrete Forms, of which the following is a full, clear, and exact description, reference being had to the accompanying drawings.

This invention relates to concrete forms, and more particularly to forms which are employed for supporting concrete from beneath until it "sets" or hardens and which will give to the under surface of such concrete the desired contour after the forms have been removed. In constructing the floors of bridges and buildings, it has heretofore been the practice to temporarily support the concrete between horizontally extending beams until it has set or hardened sufficiently, and thereafter to remove the supports. As this operation is ordinarily performed, wooden or metal plates or forms are interposed between the flanges at the bottoms of adjacent beams, being supported from beneath by platforms and jacks, necessitating the removal of both the forms and their supporting means after the concrete has set or hardened. In constructing these floors in accordance with my invention, I employ light metal sheets of the proper shape, of sufficient strength merely to carry the weight of the superposed concrete and of the workman who tamps and levels the material, the plates being provided with flanges which enable them to be supported upon the flanges of the beams; and these plates are left in place until they have so rusted or oxidized as to drop out or permit their convenient removal. In actual operation this has resulted in a great saving of labor and expense in the installation of such floors.

It is the general purpose and object of this invention to provide a temporary support for concrete floors of the character described which shall be extremely efficient for the purposes set forth and which shall be convenient of installation and economical of production. I realize this object in and through the construction of floor supporting plates illustrated in the drawings forming part hereof wherein Figure 1 represents a transverse sectional view through a concrete

floor temporarily supported by my floor plates; Fig. 2 a vertical sectional view corresponding to the line 2—2 of Fig. 1 and looking in the direction of the arrows; Fig. 3 a perspective view of one of my floor supporting plates; Fig. 4 a sectional detail illustrating a slightly modified form of such plate; and Fig. 5 a similar view of a still further modification.

Describing by reference characters the various parts illustrated herein, 1, 2 and 3 denote longitudinal beams of a bridge, the beams 2 and 3 supporting a floor 4 for the use of pedestrians and the beams 1 supporting thereupon the rails 5 of a track for cars. The beams 1 and 2 support the concrete or monolithic floor 6.

The beams 1 are of usual I-beam construction, having the top and bottom inclined flanges 1^a. For the purpose of temporarily supporting the wet concrete between the beams 1, I employ a sufficient number of sheet metal plates 7, each sheet providing a suitably shaped arch (preferably a continuous curved surface) extending from the bottom flange of one I-beam to the bottom flange of the opposite I-beam. At each end the plate 7 is provided with a flange 8 which is so shaped as to rest upon the flange 1^a of an I-beam and with an upturned flange 9 which is adapted to bear against the web 85 of such beam, the sheet being so shaped and proportioned that a continuous arch is formed between the opposed edges of the flanges 1^a. Because of the fact that the plates will not be removed, except as they rust out, they will be made as light as possible—say of 24 gage metal—and for the purpose of giving them sufficient strength to support the weight of the concrete and of the laborer who levels and tamps the concrete, each plate will be provided with a pair of corrugations 10, 11, and preferably extending downwardly from the body of the plate. These corrugations are formed so as to strengthen the plate throughout its entire lateral extent from beam to beam but without interfering with the seat which is provided between each flange 8 and the co-operating I-beam flange. It will be observed that each corrugation terminates at the flange 8 and does not extend therewith and that it extends continuously across the plate from flange to flange. This enables the

flanges 8 to fit snugly on top of the I-beam flanges, and this practically eliminates leakage beneath the flanges while the concrete is in its wet condition, making a practically 5 water-tight joint against the passage of such moisture. The provision of the flanges 9 also coöperates in securing this result as well as to prevent lateral displacement of the plates.

10 It is intended that the plates 7 shall overlap and, to facilitate this overlapping and at the same time to strengthen the temporary floor support at the joints thus formed, the corrugations 11 will be provided a short distance 15 within the lateral edges of the plate. In overlapping the plates, the edge of the corrugations 11 forms a convenient gage for an overlapping plate and forms a stop for an underlapping plate, as will clearly appear 20 from Fig. 2.

In Figs. 1 and 4 I have shown in detail a modification of the plate hereinbefore described and which modification will be employed where a plate of less than full width 25 is used, as where the space between a pair of I-beams is less than such full width. In this case, the distance between the beams 1 and 2 is less than the distance between the beams 1. The plate 7^a will be of the same 30 curvature from the I-beam 1 as is the case in the form hereinbefore described. However, because of the fact that it is of less width, the end which is opposite the flange 8 will be especially shaped to coöperate with its 35 support—shown in this case as an angle iron 12. The body of the sheet 7^a is merely extended, as indicated at 8^a, to provide a flange resting upon the angle iron and forming a substantially water-tight joint therewith. 40 The corrugations 10^a and 11^a will extend from the flange 8^a to the edge of the horizontal flange of the I-beam but will not rest thereupon.

In Fig. 5 I have shown a still further 45 modification of the plate, wherein the flanges 9 are omitted.

The concrete floor-supporting form which is herein provided possesses the following 50 advantages:—

55 (a) It may be easily installed from above, thus dispensing with the use of platforms or ladders.

(b) It is entirely supported from the 60 floor beams and possesses sufficient strength in itself to carry the load, thus eliminating the use of jacks, platforms, or other supporting devices.

(c) A substantially water-tight connection 65 is provided between its lateral edges and the beams whereby practically no liquid concrete material will leak therearound during the drying or setting stage.

(d) The cost of the plates is inconsiderable as compared with the expense of setting 70 up and removing the forms which have

universally been employed heretofore for the purpose of supporting concrete flooring.

(e) Having a close seat between the plate flanges and the beam flanges provides a solid bearing for the concrete floor on the beam flanges.

Having thus described my invention, what I claim is:—

1. As a new article of manufacture, an arched sheet metal floor plate having a substantially flat flange at each end thereof and provided with two corrugations extending thereacross between but not including said flanges, one of said corrugations being located adjacent to a lateral edge of said plate. 75

2. As a new article of manufacture, an arched sheet metal floor plate having a flange at each edge thereof and provided with corrugations extending thereacross and between but not including said flanges, one of said corrugations being located adjacent to a lateral edge of said plate. 85

3. As a new article of manufacture, a sheet metal plate having at each end thereof a substantially flat flange adapted to seat upon and form a substantially water-tight joint with the flange of a floor supporting beam and having outside of each of the first mentioned flanges a flange adapted to bear against the web of such beam. 90

4. An arched sheet metal floor-supporting plate having at least one edge thereof a substantially flat flange adapted to rest upon the flange of a floor supporting beam and having a corrugation extending thereacross 100 as far as but not including said flange, said corrugation being located adjacent to a lateral edge of said plate.

5. A concrete floor supporting form comprising a plurality of arched sheet metal 105 plates each plate being provided with substantially flat flanges adapted to rest upon the flanges of the floor supporting beams, each plate having two corrugations extending thereacross between but not including the flanges thereof, one of said corrugations being located adjacent to a lateral edge of said plate and the plates behind overlapped whereby a continuous floor support will be formed. 110

6. A concrete floor supporting form comprising a plurality of arched metal plates each having at least one edge thereof a flange and each having two corrugations extending thereacross as far as said flange, one of said corrugations being located adjacent to a lateral edge of its plate and the plates being overlapped whereby the corrugation at the lateral edge of each plate may coöperate with the corrugation of an adjacent 115 plate to provide a continuous floor support. 120

In testimony whereof, I hereunto affix my signature.

HARRY O. DAVIDSON.
